UNITED STATES PATENT OFFICE.

LANSING ONDERDONK, OF NEW YORK, N. Y.

STAMP-AFFIXING MACHINE.

1,289,237.

Specification of Letters Patent. Patented Dec. 31, 1918.

Application filed July 5, 1910. Serial No. 570,234.

To all whom it may concern:

Be it known that I, LANSING ONDERDONK, a citizen of the United States, residing in the borough of Manhattan, city, county, and 5 State of New York, have invented a new and useful Improvement in Stamp-Affixing Machines, of which the following is a description.

This invention relates to machines which 10 may be used for either vending articles of a predetermined character and size, or for delivering stamps or similar articles and affixing them to a given surface. Particularly my invention relates to, and is illustrated in 15 connection with, a stamp-affixing machine; but, certain features or devices or mechanisms may be used without others, thus rendering the machine capable of use for various purposes.

20 Among the objects of my invention may be noted the following: to provide a machine by which articles can be delivered successively and only one at a time, irrespective of adjustments for the size of the article; to 25 provide a feeding mechanism which will deliver but one article during a complete operation of the machine and which cannot be made to again deliver an article until the actuating mechanism has been restored to initial 30 position preparatory for another functional operation; to provide a stamp-affixing machine wherein the liquid-delivering mechanism is arranged remote from the stamps or the adhesive surface thereof; to provide 35 a machine of the character stated so constructed as to provide the largest possible liquid reservoir in the smallest possible space, and so constructed as to enable the reservoir to be readily refilled, and so as to be entirely 40 independent of the feeding and delivering mechanism for the stamp; to provide means by which the water to be delivered to the stamp can be measured so as to avoid waste and prevent an excess of moisture 45 being imparted to the stamp; to provide a feeding mechanism, for the strip or web of stamps, capable of being so regulated as to deliver the stamps accurately and uniformly one-by-one to the cutting mechanism; to provide a feeding mechanism which 50 can be regulated or adjusted to a nicety for the purpose of accurately delivering the stamps, or similar articles, consecutively, or so as to uniformly deliver the same size or 55 strip, irrespective of its character; to provide means by which the cutting mechanism

is compelled to perform its functions accurately in consonance with the feeding mechanism, whereby a given length of the strip or article is uniformly fed, cut and delivered 60 for each complete cycle of movements of the machine; to provide means whereby, irrespective of the quantity of water in the reservoir, the same amount will be measured and delivered for each operation of the machine; 65 to provide a single locking means for holding the reservoir and stamp-receptacle closed; to provide means whereby, for each movement of reciprocation of the plunger, the feeding mechanism will be caused to operate and 70 which requires a complete reciprocation of the plunger to feed a single stamp from the machine; to provide means by which, after a stamp has been completely fed and delivered, no further delivery of stamps can be 75 obtained; to provide means whereby the movements of the feed-drum or wheel can be regulated without altering the relation and cooperative action of the drum - actuating mechanism; and to provide certain novel 80 details of construction for spraying the stamps or article in contradistinction to moistening the same by a means in contact with the latter, as well as other details of construction which tend to simplify the machine, render it certain, effective and positive in operation, insure its functional operations without fail for every complete action of the machine, and which enables the machine to be used for various purposes with or without 85 the moistening device.

With the above objects in view, and others which will be detailed during the course of this description, my invention consists in the parts, features, elements and combinations of 90 elements and mechanisms, all as hereinafter described and claimed.

In order that my invention may be clearly understood, I have provided drawings wherein:

Figure 1 is a central, vertical section taken from front to rear of the machine and showing important details of my invention;

Fig. 2 is a vertical section taken substantially on the line 2—2 of Fig. 1;

Fig. 3 is a perspective view of the face-plate and of a portion of the stripper-plate;

Fig. 4 is an elevation showing details of the feed-adjusting means, the two parts being separated and shown in position ready 110 for assembling;

Fig. 5 is a longitudinal, central section

100

105

110

through the feed-adjusting means, parts being broken away, and showing a portion only of the feed-drum;

Fig. 6 is a detail view showing the locking-device by which the reservoir is held in operative position;

Fig. 7 is a plan of the key for manipulating the locking-device of Fig. 6;

Fig. 8 is a side elevation and partial section of the machine, showing the cover for the reel-receptacle open and also showing the reservoir in an inoperative position;

Fig. 9 shows one form of a liquid-measuring device, or valve construction, contemplated by my invention;

Fig. 10 is an end elevation of the valve of Fig. 9;

Fig. 11 is a perspective view of another form of water-measuring device or valve contemplated by my invention;

Fig. 12 is a perspective view of the reservoir and certain parts carried thereby;

Fig. 13 is a section substantially on the line 13—13 of Fig. 8, showing the structure 25 of the air-valve;

Fig. 14 is a detail sectional view of part of the mechanism shown in Fig. 13;

Fig. 15 is a side elevation of the device opposite that of Fig. 8, showing the means for 30 actuating the water-measurer or valve, certain of the feed-gears being shown in dotted lines;

Fig. 16 is a plan of the cutter-head, parts being broken away to show the details of 35 construction;

Fig. 17 is a bottom plan view of the machine forward of the reservoir, showing the mode of securing the face-plate in the machine;

Fig. 18 is a section substantially on the line 18—18 of Fig. 15, the parts above the bell-crank being omitted;

Fig. 19 is an elevation of a part of the feed-actuating gears, showing details of the 45 latter; and

Fig. 20 is a perspective view of the reel-holder.

Primarily, I desire it understood that certain of the features of my invention are 50 not restricted to use in a stamp-affixing machine, but may be employed in, or constitute, a vending machine, such parts being the cutter and feed; and though the moistening mechanism may be a part of the machine at 55 all times, the latter can be converted into a vending machine by simply putting the moistening mechanism out of operation. Or, the moistening mechanism may be omitted, thus making a vending machine. Hence, the 60 convertibility of the machine is an important feature of my invention, and though I have chosen to show my invention in a stamp-affixing machine, I do not purpose being limited thereto, as my machine is adapted 65 to feed strips of material of various kinds

and sever therefrom sections of various sizes, according to adjustments, capable of various uses. Therefore, I purpose that the term "stamp", employed herein, shall not be a word of limitation, but shall be comprehensive of any small piece or strip of material, whether gummed or not, or which can be rendered adhesive by the application of moisture or an adhesive substance.

Referring to the drawings, the frame is 75 made in two parts indicated by 1 and 2, held together by a screw 3 at the front and top of the machine and at the rear of the machine by the screw 4, passing through vertically-extending ears 5, said screw forming the 80 hinge for the cover 6 of the stamp-receptacle, said cover having a lug 7 extending between the two ears 5, through which the screw 4 passes. Though I have shown screws for holding the several parts together 85 as described, and other parts as hereinafter described, I preferably use rivets as, in so doing, a machine is produced which cannot be taken apart nor tampered with in any way so as to obtain the stamps or destroy the 90 record of delivery thereof; that is to say, I purpose combining with my machine a counting or registering device operated by or with the feeding mechanism so that every article delivered or stamp affixed will be recorded or counted and a permanent record made thereof. I have not shown such device in this case as it forms the subject-matter of another application now under preparation. Hence, the use of rivets to 100 permanently fix the parts together becomes important in that it produces a structure which cannot be cheated, nor stolen from. The stamp-receptacle is or may be circular 105 in form and one-half thereof is formed in the cover 6 and the other half 8 is formed in the frame of the machine, as clearly shown in Figs. 1 and 8. The rear end of the cover is provided with a catch 9, which co-operates with a latch 10, formed on the upper end at the rear of the reservoir 11. The cover is provided with recesses 12, at its opposite sides, corresponding to recesses 13 in the frame for the reception of the oppositely-extending journal-pins 14, see Figs. 8 115 and 20, of the reel-holder, which consists of two like members, each of which is provided with a support 15 at the upper end of an arm 16, the lower end of which is bent at a right-angle, as shown at 17, and provided 120 with wings 18, which embrace the portion 17 of the corresponding member. The pins 14 journal in the bearings afforded by the recesses 12 and 13 in the frame and cover, respectively, see Fig. 8, and thus support the reel or web 19 in proper position in the machine. The arms 16 are resilient and can be drawn apart to enable the supports 15 to be separated for the admission and removal 125 of the reel of stamps, the lateral adjustment 130

of arms 16 being to the extent of the slot 20. The wings 18 keep the arms and supports 16 and 15 in proper relation while being adjusted and the pin 21 prevents the parts 5 from falling apart, said pin being fixed to one part 17 and extending through slot 20 and headed as shown in Fig. 20. The normal operative position of the reel and holder is shown in Fig. 1. The reservoir 11 is 10 journaled in the frame upon the pin 22, which extends from side to side of the frame, as clearly shown in Fig. 13. The journal 23 of the reservoir is enlarged at one end to provide a chamber within which is set a 15 valve 24, in the form of a hollow cylinder provided with an aperture 25, communicating with a tube 26, extending from top to bottom of the reservoir 11, said tube communicating at its forward end with the 20 measuring-device, as will be presently described. The valve 24 is also provided with a smaller aperture 27, which communicates with a passage 28, extending through the top portion of the reservoir-frame and into the 25 said reservoir. A tube 29 extends along the outside of the frame, as shown in Figs. 8 and 13, and communicates with a passage 30 in the frame, said passage entering a chamber 31, formed in said frame adjacent the 30 valve 24. By this means, the air-tube 29 communicates with the valve 24 to supply air to both the reservoir and the measuring-device, as presently described. The valve 24 may be opened or closed by means 35 of a finger-piece 32, operating between shoulders 33 of the reservoir-frame, and by manipulating which valve its apertures can be thrown into and out of registry with the aperture in the frame of the reservoir and the 40 tube 26, respectively, as shown in Figs. 13 and 14. At its lower forward end, the reservoir is provided with a chamber 34, extending transversely thereof, in which is set to rotate the cylindrical valve or measuring- 45 device 35, one end of which is screw-threaded into the chamber 34, as indicated at 36, and the other end of which is provided with the double mutilated-gear 37, coöoperating with a bell-crank lever fulcrumed at 38 to the 50 frame of the machine, see Figs. 11 and 15. The gear 37 has its teeth meshing with the segmental-rack 39, on one arm of the lever. The rack 39 has peripheral and lateral teeth, which coöperate with the double gear 37, as 55 shown in Fig. 15. The other arm of the bell-crank lever is provided at its outer end with an elongated slot 40, whereby said lever is manipulated, as presently described. The action of the lever is limited in opposite 60 directions by the stop-lugs 41, carried by one portion of the gear 37, as clearly shown in Fig. 15, said lugs coöoperating with the flat portions at opposite ends of the segmental-rack 39. The valve 35 is provided 65 with the large aperture 42, in one side, and, about a quarter turn therefrom and a little to one side thereof, with a smaller aperture 43. The end of the valve 35 is provided with a screw-plug 44, by means of which the valve-chamber can be made larger or 70 smaller, as desired, said plug being set well within the end of the cylinder of the valve so that extreme adjustment outwardly will not interfere with the longitudinal movement of the valve. The bell-crank lever, 75 when actuated, rocks the valve 35, resulting in giving thereto oscillatory motion and longitudinal reciprocation within the chamber 34, the result of which is to cause the large aperture 42 to coöperate with a passage 45, 80 extending into the said chamber 34, and with a spraying-device 46; also to cause the smaller aperture 43 to coöperate with the tube 26, as clearly shown in Figs. 1, 8, and 12. Referring to Figs. 1 and 13, it will 85 be seen that the passage 45 extends into the reservoir as near the bottom as is practicable without weakening the bottom of the structure. This enables practically all the water to be delivered to the valve. It will also be 90 seen that it requires but a quarter turn of the valve to take in the water and deliver it to the spraying-nozzle and that the compound movement of the valve results in 95 quickly opening and closing the several 95 ports with comparatively little movement of the valve. The spraying-device 46 consists of a nozzle provided with a plurality of small apertures 47, through which the water in the reservoir 11 is sprayed after 100 being received in measured quantity in the valve 35. The aperture 43 also communicates with the tube 26, through the wall of the reservoir, and thus air is admitted through said tube into the said valve to 105 force the water received by the latter through the spraying-nozzle 46. The apertures 47, in nozzle 46, are directed upwardly at angles such that, as the stamp is fed out preparatory to being cut off, the 110 spray will be directed toward the center of the stamp, thus completely moistening its surface. This is an important feature; but, it should be understood that, though I have 115 provided means by which practically the entire surface of the stamp will be sprayed, it is not necessary that the device shall operate to so spray said stamp, as a small quantity of fluid sprayed upon the center, or substantially the center of the stamp, will be 120 uniformly spread over the surface thereof when pressure is applied thereto for affixing it to a given surface. The reservoir at its rear is provided with the transparent 125 wall of mica, glass, or other suitable material, indicated by 48 and set therein in any approved manner to prevent leaking; and the bottom of the reservoir may consist of a separate plate 49, dove-tailed at its forward end into the bottom of the reservoir 130

and at its rear end upturned and secured by means of a screw 50 to the lower edge of the rear wall of the reservoir, as clearly shown in Figs. 1 and 8. The reservoir is 5 also provided with an inlet extension 51, sealed by a removable screw-plug 52. The height of the water in the reservoir can be readily seen through the transparent wall 48, and the reservoir readily filled through 10 the inlet 51. The reservoir 11 is locked in operative position by a latch 53, fixed to a stud 54, capable of turning in the bottom of the reservoir 11, see Figs. 2, 9, 12 and 13. The latch slides horizontally from the reservoir 15 into a recess 55 in the frame-part 2, see dotted lines, Fig. 8, when the parts are in the position of Figs. 1 and 2; and may be unlocked by inserting the key 56 in the head 57 of the stud 54 and turning the latter into 20 position as shown in Fig. 2.

The tube 29, leading to the valve 24, communicates with the passage 58, extending vertically through the semi-cylindrical, screw-threaded portion 59 of the wall 2 of 25 the frame, said semi-cylindrical portion and its corresponding portion 60 of the frame-portion 1 forming the bearing for the reciprocating plunger 61, the parts being held together by means of the cylinder 62, internally screw-threaded at its lower end to 30 operate with the screw-threaded frame-portions 59 and 60. At its upper end, the plunger 61 has a screw-threaded extension 63, entering the head 64 of the sleeve 65, the 35 lower end of which is screw-threaded and shouldered for coöperation with a closure-sleeve 66, correspondingly formed to engage therewith, packing 67 being placed between the parts to form an air-tight joint and 40 make the chamber within the cylinder 62 and sleeve 65 air-tight, thus producing a compression-chamber for the air employed to spray the fluid upon the stamp. The head 64 and the plunger 61 are sustained normally 45 in elevated position by means of a coiled-spring 68, surrounding the plunger 61 within the casing formed by the cylinder 62 and sleeve 65, said spring resting at one end upon the parts 59—60 of the casing and at the other 50 end engaging the flange 69 of the plunger. The head 64 is provided with one or more air-inlet passages 70, communicating with the interior of the parts 62—65, but periodically opened and closed by means of a ring-valve 71, with sufficient clearance between the latter and the bottom wall of the head 64 to 55 permit slight movement of said valve for the ingress of air according to the direction of movement of the plunger 61. When the 60 plunger is depressed, the valve-ring 71 is forced by the compressed air within the chamber into tight engagement with the bottom of head 64, thus closing the air-passages 70 and permitting the air to be forced 65 through the several passages and valves to

the spraying device. This construction is important since it is compact, strong and simple and combines several important functional devices in a small space, such as the compression mechanism, the spring 68, and 70 keeps dust and grit from the operating parts and prevents interference with the latter. Being thus housed and arranged, the parts are not liable to get out of order and will always perform their functions properly. The 75 plunger, near its lower end, is provided with a rack 72, and on its opposite side with a longitudinal groove 73, extending to near its upper end, the function of which will be presently explained. 80

The plunger 61, at its extreme lower end, is provided with a cutter-holder and stamp-presser 74, secured thereto in any suitable manner, but shown as held thereto by a screw-threaded connection 75 and a locking-screw 76, passing through the said head and into the lower end of the plunger, as clearly shown in Figs. 1, 16 and 17. The member 74, as shown in Fig. 18, has two oppositely-extending pins, one of which 77 is short and 90 extends into a groove 78, shown in Figs. 17 and 18, and by dotted lines in Fig. 8, and formed in the inner surface of the frame-portion 2 and the other of which 79 is long and extends through the slot 80 in the frame-portion 1 and enters the slot 40 in the long arm of the bell-crank lever so as to actuate the latter. The holder 74 is recessed laterally, as at 81, see Figs. 1 and 16, for the reception of the cutter-blade 82, which is provided with the wedge-shaped, angular cutting-edge 83. In rear of the recess 81 are two parallel bores 84, in which are housed coiled-springs 85, the normal tendency of which is to force the cutter-blade outwardly into yielding contact with the surface of the face-plate 86, the details of which are shown in Fig. 3, and which is secured to the opposite frame-portions 1 and 2, in any suitable manner, as by screws 87 passing through the apertures 88, see Fig. 17, thus holding the face-plate firmly in position for coöperation with the cutter-blade, this connection also aiding in holding the frame-parts together. The face-plate is provided with an inclined slot 89, the lower edge of which is beveled for the purpose of producing a ledger-blade 90, for coöperation with the cutting-edge 83 of the cutter-blade, and the inclination of the slot 89 is for the purpose of enabling a 100 shearing action to take place in the cutting operation, thus facilitating severing the stamps from the strip or web 19. The springs 85, obviously, constantly tend to press the cutting-edge 83 of the blade 120 against the face-plate so as to keep the same constantly in coöperative relation with the latter. The slot 89 provides for the passage of the stamps so as to present the same properly to the cutting and moistening mecha- 130

nisms. The face-plate 86 is also provided with a recess 91, into which projects the nozzle 46 and through which the spraying takes place. It should be noted particularly, at 5 this point, that the delivery of the articles from the web takes place at a point remote from the moistening-device and that the said articles or web are never in contact with the moistening-device, do not wipe over the 10 same, as is common, but are always fed and delivered at a distance from the moistening-device so that there is no possibility of the adhesive surface of the strips or articles becoming moistened except at the time and just 15 to the extent desired and necessary for affixing the severed articles to the predetermined surface. This is one of the important features of my invention and upon it I desire to lay great stress.

20 As shown in Figs. 1 and 12, the reservoir 11 has secured to its upper surface the stamp or strip guide 92, screws 93 being shown for securing the same in position, and the strip-guide being made to conform 25 substantially to the shape of the upper surface of the reservoir and at its lower end curved, as at 94, to conform to the feed-wheel presently described. In the curved portion 94 are arranged parallel slots 95, 30 through which project the pins of the feed-wheel, and the forward end of said curved portion 94 is at rest upon the forward end of the reservoir above the valve 35 and within a groove 96 formed in said surface, to 35 prevent said strip-guide from being laterally displaced. At its forward end, the strip-guide coöperates with the stripper-plate 97, extending across, and secured by means of screws 98 to, the face-plate 86, 40 said stripper-plate being angular in form and being located so that its lower surface will be just above the slot 89 in said face-plate 86. The horizontal portion of the stripper-plate 97 is provided with a series of open- 45 end slots 99, registering with the slots 95 in the strip-guide 92, and said horizontal portion is spaced from the curved portion 94 of said strip-guide sufficiently to permit the free passage of the strip or web 19 between 50 the two. The slotted edge of the stripper-plate extends forward under the feed-wheel, as clearly shown in Fig. 1. The two parts 1 and 2 of the frame of the machine are provided with open-end slots which, when said 55 parts are placed together, form a continuous slot 100, through which, as shown in Fig. 1, the web 19 is guided to the feed-wheel and between the latter and the strip-guide around to and under the stripper-plate and 60 through the slot 89 in the face-plate. If desired, the slot 100 may be omitted; or, as an alternative mode of threading the machine with the strip or web 19, the latter may be led around the edge 8^a, of the recep- 65 tacle, and over the surface of the strip-guide

92, as shown by dotted lines 8^a, in Fig. 1. The front of the machine is also provided with a transparent plate 101, through which can be seen the operation of certain of the parts so as to determine whether the stamps 70 are being properly cut and fed.

The feeding mechanism is also an important feature of my invention and upon its construction and its functional mode of operation I desire to lay considerable stress, 75 as it is important that the strip should be fed uniformly and positively and under mechanical control in such manner that stamps cannot be drawn out of the machine by hand or obtained in any way except as is intended 80 by the operation of the plunger. This feeding mechanism, as shown in Figs. 1, 2, 4, 5, 8 and 19, consists of the rack 72, carried by the plunger 61, which coöperates with two separated pinions 102—103, arranged one 85 above the other and loose upon the shafts 104—105, respectively, journaled in the opposite frame-portions 1 and 2. The gears 102—103 are provided, respectively, with clutch-members 106—107, which coöperate 90 with corresponding clutch-members 108—109, respectively, the one 108 carrying a gear 110, which meshes with a gear 111, carried by the clutch-member 109. The clutch-member and gear 108—110 are loose upon the 95 shaft 104 and the clutch-member and gear 109—111 are loose upon the shaft 105. A spring 112 normally holds the gear 102, with its clutch-member 106 in engagement with the clutch-member 108, and a spring 113 100 performs a like function with reference to gear 103 and its clutch-member 107 and the clutch-member 109. The gear 114, carried by the shaft 115, is also journaled in the frame-portions 1 and 2, said shaft 115, 105 at its other end, being provided with a mutilated-gear 116, the character of which is shown in Fig. 19, which in turn meshes with the mutilated-gear 117, carried by the feed-shaft 118, also journaled in the frame-parts 110 1 and 2 below the shaft 115, see Figs. 1 and 2. The mutilated-gear 116 has less than half its periphery provided with teeth 119, while the gear 117 is provided on its periphery with two sets of teeth 120, of like character, each extending around less than half of the periphery of the gear, said sets of teeth being separated by curved blank-portions 121, oppositely-disposed on the periphery of the gear 117 and separating the gear-teeth 120 from each other. The periphery of the gear 116, for more than half of its circumference, is smooth, as shown at 122, and is provided on its face with a disk 123, smaller in diameter than the gear 116 and 125 provided with a single radial tooth 124, extending to the periphery of the gear 116 and arranged at one side of the teeth 119 at one end of the said smooth portion 122. Likewise, the gear 117 is provided with a 130

disk 125, of smaller diameter than the said gear and provided with two opposite radial teeth 126—127, projecting to the periphery of the gear 117 and arranged so that the tooth 126 is at one end of the blank-portions 121, and the tooth 127 is at the opposite end of the opposite blank-portion 121. The disks 123 and 125 are arranged in the same vertical plane so that the tooth 124 will engage successively the teeth 126 and 127. This structure of the mutilated-gears and coöperating-teeth and smooth-portions is for the purpose of producing an intermittent feed of the strip for just the desired distance and at just the desired time during both the up and down movements of reciprocation of the plunger 61. The mutilated-gear 116 and its toothed disk 123 are fixed to the shaft 115, while the mutilated-gear 117 and its toothed disk 125 have a cone bearing upon the feed-shaft 118, as shown in details in Fig. 5, and one portion 128 of which is carried by the feed-shaft 118 and enters the corresponding hub 129 of the mutilated-gear 117, said hub being extended laterally from said gear and provided with notches 130, see Fig. 4, in its periphery and with a bearing 131 for receiving a ratchet-segment 132, projections 133 of which enter the notches 130 so as to enable the ratchet-segment and mutilated-gear to move together. The shaft 118 extends beyond the hub of the mutilated-gear 117 and has fixed thereto the adjusting-pawl 134, carrying a spring-controlled pin 135, at its upper end, said pin being formed wedge-shaped at its outer end, as at 136, for coöperation with the teeth of the ratchet-segment 132 so as to hold said segment in adjusted position and in engagement with the said pawl 134. The pawl 134 is also provided with a laterally-extending pin 137 for coöperation with the opposite ends of the segmental-rack 132, to thus limit the extent of movement or of rotation of said pawl. The wedge-shaped portion 136 of the pin 135, which coöperates with the ratchet-teeth of the segment 132, is caused to normally project outwardly by the coiled-spring 138, contained in the chamber 139 of the pawl, which spring surrounds the stem of the pin and engages at one end the head 140 thereof and at the other end the end of the chamber in said pawl. The detent-pin 135 may be grasped by the knurled-head 141 on the other end of the pin, which is prevented from turning and maintained in operative position by lugs 142 entering the recesses in the end of the pawl. When the pin 135 of the pawl 134 is drawn out, the wedge-shaped portion 136 is retracted from the ratchet-teeth and the adjusting-pawl 134 can be moved circularly relatively to the segment so as to adjust the feed-shaft carrying the feed-drum without changing or moving the ratchet-segment and thus without

altering the coöperative relation of the mutilated-gears. This is important, as adjustments of the feed-drum may have to be made from time to time and the relation of the mutilated gears must not be disturbed. By making the said gears and the feed-adjusting means independent of each other, this function can be accomplished. The feed-shaft 118 carries an adjusting-sleeve 144, for the feed-drum, said sleeve extending from near the cone-bearing at one end of the feed-shaft to beyond the opposite end of the latter, and being supported in the frame-portion 2, as shown in Fig. 2. In this end of the sleeve, a set-screw 145 is threaded, said screw having a reduced extension 146, threaded into the hollow end of the feed-shaft. The pitch of the screw-threads of the two portions of the adjusting-screw is different, so that, for a slight movement or adjustment of the screw, a considerable movement of the adjusting-sleeve 144, on and relatively to the feed-shaft, is obtained. One or more pins 147, carried by the feed-shaft, extend through the sleeve and prevent the latter from turning on said shaft, but permit longitudinal movement of the shaft and sleeve relatively, as just stated. Near its opposite ends, the adjusting-sleeve 144 is provided with circular, beveled flanges 148, the bevel or inclination of the two flanges being in the same direction and the two said beveled flanges coöperating with like circular flanges 149, projecting inwardly from the feed-drum. The feed-drum consists of a barrel provided with longitudinal slots 150, open at one end and closed at the other, the closed ends of the slots alternating with open ends of adjacent slots, thus leaving at opposite ends of the drum connecting-webs 151, for securing the several segmental portions of the drum together and holding the same in circular form. By thus constructing the drum, the webs or sections 152 are made resilient so as to readily yield or flex when the wedge-shaped flanges thereof coöperate with the wedge-shaped flanges of the adjusting-sleeve under the longitudinal adjustments of the latter relatively to the drum. In order to properly sustain the feed-drum and prevent it from having longitudinal movement relatively to the sleeve or the shaft, end-supporting collars 153 are provided, the hub of one of which engages a bearing of the frame-portion 1, and the other of which engages the cone-bearing 128 of the feed-shaft. Each of the resilient webs 152 is provided with one or more projecting-pins or sharp points 154, extending therefrom at a right-angle and arranged on the several webs in staggered relation. These pins may be set in the drum by threaded-heads 155, so as to be readily replaced in event any should become broken. The collars 153 are shouldered, as shown

in Figs. 2 and 5, so as to properly seat the feed-drum and prevent it from being moved endwise when its diameter is increased or decreased by the adjusting means described.

Having thus described my invention in the matter of the detail construction, the mode of operation will be readily understood upon reference to Figs. 1, 2 and 8. The reservoir having been filled and the web or reel of articles having been placed in the receptacle 8, the end of said web will be threaded through slot 100, or around the frame-part 8^a, around the rear of the feed-drum and under the stripper-plate 97, through the slot 89, in the face-plate 86, the end of the web being drawn through said slot to the extent of approximately one-half the length of the stamp, as shown in Fig. 1. The cover 6 being closed, the reservoir will then be swung upon its axis into the closed position of Fig. 1 and the latch 53 turned by key 56, thus locking the reservoir. The cover 6 becomes locked when the reservoir is swung into closed position by coöperation of latch and catch 9—10 and cannot be opened until the reservoir is again swung to the position of Fig. 8. As the reservoir is swung into closed position, the strip-guide 92 forces the web upon the pins 154 of the feed-drum so that said web cannot be moved except by said drum. This mode of locking the cover and reservoir I consider an important feature of my invention, since by the one locking means controlled by a key the stamp-web and reservoir are held in operative position and the stamps are sealed against theft or removal. The manner in which the machine can be opened, as shown in Fig. 8, is an important feature of my invention, since it simplifies the threading of the machine and makes it easy to handle the web and inspect the parts of the machine. The valve 24 is now turned to admit air into the reservoir and into the tube 26. The machine being now ready for operation, the hand of the operator will be pressed upon the head 64, so as to force the plunger 61 downwardly and thus cause its rack 72 to drive the gears 102 and 103. The clutch-part 106 of the gear 102, on the downward movement of the plunger, will engage the clutch-part 108, so that the gear 110 will be driven by said clutch. The gear 103, will also be rotated by the rack of the plunger to cause its clutch member 107 to move away from the clutch-member 109 and thus have no driving action. The gear 110 will drive the gear 111, which, in turn, will drive the gear 114, carried by the shaft 115, so as to drive the mutilated-gear 116. The teeth 119 of this gear being in mesh with one set of the teeth 120, of the gear 117, the latter will be driven, thus actuating the feed-shaft 118, to drive the feed-drum for a predetermined distance, and giving a definite feed movement to said feed-drum. This brings the entire stamp or article through the face-plate, the feed being finished just before the cutting-edge 83 of the cutter-blade 82 reaches the ledger-blade 90, so that the stamp has been completely fed through the slot 89, in the face-plate 86, before the cutting-device severs the stamp from the web. The complete feed movement is accomplished on the down stroke of the plunger 61 and before the cutter comes into operation, and is the result of the coöperation of the mutilated-gears 116 and 117. After this feed movement has been accomplished, the smooth portion 122, of the gear 116, coöperates with one of the smooth portions 121 of the gear 117, thus stopping the feed movement of the feed-drum, the two said smooth portions of the mutilated-gears sliding relatively to each other and no driving action being accomplished by them. This locked position of the feed-drum continues until the tooth 124 of the disk 123 on gear 116 engages with one of the teeth, for example, 127, of the gear 117, thus driving the latter slightly forward to bring the other set of gear-teeth 120 into engagement with the gear-teeth 119, whereupon another feed-movement of the feed-drum may be accomplished in the same direction. This occurs on the return or up-stroke of the plunger 61, under the influence of the spring 68, after the hand of the operator has been lifted or removed; that is to say, on the up-stroke of the plunger, the gears 102 and 103 are driven in the opposite direction, but the gear 103 becomes the feed-driving gear, while the movement of the gear 102 is idle, since the gear 103 is moving in the direction requisite for causing its clutch-member 107 to drive the clutch-member 109, the gear 111 of which will mesh with the gear 110 and move its clutch-part 108 around to meet the part 106, the gear 111 also meshing with gear 114 to drive it in the same direction for causing the mutilated-gears, previously brought into coöperation, to operate to feed the drum. The direction of these movements is shown by arrows in Fig. 1. When the gear 103 is performing its idle rotation, it also slides laterally on the shaft 105 and compresses the spring 118, this being the result of the coöperation of the clutch-members 107 and 109 in a contra-functional direction. This is also true of gear 102 when the gear 103 is performing a function. And the two gears 102 and 103 are returned to functional position by their respective springs just before the plunger 61 reaches the extreme of its opposite movements, thus one of the clutch-devices being always ready for operation to drive the feed-drum. On reference to Fig. 2, it will be seen that the two clutch-devices 106—108 and 107—109 are reversely made, so that only one can

perform a feeding function during any given movement of the plunger 61. When one clutch is driving the feed-drum, the parts of the other are turning away from each other, and as soon as a feeding function has been accomplished by one clutch-device the parts of the other clutch-device coöperate to lock the gears against another feeding operation in that direction until the plunger has been moved to the opposite extreme. Hence, when the feed is accomplished by one movement of the plunger, further feed by a further movement of the plunger in the same direction is automatically prevented. The travel of the plunger 61, either down or up, is sufficient to turn the gears 102, 103, 110 and 111 half-way around, gears 110 and 111 turning oppositely to gears 102 and 103, respectively, thus causing the respective clutch-parts 106—108 and 107—109 to assume a position under the influence of the springs 112 and 113, such that when the plunger 61 is again moved one or the other of said clutches will have its parts brought into engagement for driving the feed-drum. The result of this combination and arrangement of gears and clutches is that, no matter which way the plunger 61, with its rack 72, moves, the gears 110, 111, 114, 116 and 117 are always driven in the same direction, and that the plunger and rack must be moved far enough in either direction to carry the inoperative clutch and respective gear by each other far enough for either the spring 112, or 113, to slide its respective gear and clutch into position for the coöperating clutch to come into engagement when the movement of the plunger is reversed, or no movement of the gears 110, 111, 114, 116 and 117 will take place. When the plunger 61, with its rack 72, is driven a distance in excess of that necessary to turn the gears 102—103 half-way around, the clutches,—correlating, but inoperative, by reason of the direction in which the rack 72 is traveling,—will pass by each other more or less according to the amount of this excess movement of the plunger. Consequently, on the reverse movement, the plunger will travel the amount of the excess movement before the correlating clutches will come together and cause the turning of the gears 110, 111 and 114 to be driven by it. Hence, a predetermined movement of the plunger and its rack 72 must take place to insure the turning of the feed-drum and strip fed by it. This predetermined movement of the plunger is such as to limit the gears 110, 111 and 114 and mutilated-gear 116, to one complete revolution, to one complete reciprocation of the plunger and its rack 72 and one-half of a revolution of the feed-drum, no matter how far the rack 72 may be driven; nor will a successive revolution of these gears take place until the predetermined

movement is given the plunger. Furthermore, should either of the gears 110, 111, 114 and 116 be turned by hand, or means other than the rack 72, the opposite way from that in which they are being driven by the plunger and rack 72, they could be turned only until the other coöperating clutches come into engagement, which would be turning these parts back to their starting point. Excess movement of the plunger results in lost motion or dwell at whichever end of the stroke the excess motion occurs. Thus, by making the excess motion greater at one end than the other, or if both ends of the plunger have an excess stroke, the greater the dwell will be. Hence, it can be readily understood that the positioning can be made of the rack 72 and the gears 102 and 103, relative to each other and to the clutches 106 and 107, to give more or less dwell at one end of the plunger's stroke than at the other, which, together with the peculiar construction and coöperation of mutilated-gear 116 with that of mutilated-gear 117, enables the amount of dwell, before or after feeding the stamp preparatory to cutting or moistening it, to be varied in the assembling to suit desired conditions; also, that one set of coöperating clutches, as 106—108, are a check against clutches 107—109 and their respective gears being turned in an opposite direction beyond a portion of the length of a single stamp, aside from the limit provided by the construction and coöperation of the mutilated-gears, which control the stamp-feeding drum; also, the combination of gears 102, 103, 110 and 111, and clutches forming part of them, permits of one-half of the stroke of the plunger 61 to drive the feeding-drum the desired distance that would be required if only gears 102 and 110, or 103 and 111 were used, for the reason that one set does part of the required work when the plunger is going one way and the other set the remaining portion of the work when the plunger is going the opposite way. Moreover, the plunger must be driven its full stroke in order that the clutches, which feed in the opposite direction, may become engaged. Otherwise, no feeding will take place. The feed-drum shown is the length or width, according to the way it may be desirable to feed the stamps, of two stamps in circumference and, as the up-and-down movement of the plunger gives the mutilated-gear 119 one complete revolution, it is evident that it takes two complete reciprocations of the plunger and, consequently, two revolutions of gear 119 and intermediate gears to turn the feed-drum once around; and that whatever the relative position of all other parts may be when the smooth or convex portion 122 of gear 119 is coöperating with the concave portion 121 of muti-

lated-gear 117, the feed-drum controlled thereby is locked against being turned until the operation of the plunger brings about proper relations of intermediate parts for 5 advancing the feed. I prefer to cause a half feed-movement of the feed-drum for every stroke of the plunger for the reason that the stamp thereby is never wholly projected beyond the face plate until desired for use. A 10 downward stroke of the plunger completes the feed-movement and simultaneously severs the stamp from the web, sprays and puts it in place. Hence, it being understood that the first portion of the feed-movement is 15 produced on the up-stroke of the plunger and the last portion of the feed-movement is on the down-stroke of the plunger, and though on the up-stroke of the plunger the stamp is thus left half protruding through 20 the face-plate, a succeeding stamp cannot be removed without tearing or mutilating it. I wish it understood that in combination with a common counting device operated by an extension to the feed-drum, previously 25 referred to as being part of another application, it would be practically impossible to obtain any stamps from this machine without recording the same or mutilating them so as to make them valueless. 30 While the foregoing feeding operations are being accomplished, the measuring-device is being operated to take up and deliver a pre-determined quantity of liquid to the surface of the stamp projecting through the face-plate and just prior to its being affixed. This 35 is accomplished by the rotation of the valve 35, caused by the bell-crank lever, to which vibratory movement is imparted by the pin 79, projecting from one side of the cutter-head 74. The upward incline given to the 40 slot 40, in the long arm of the bell-crank lever, is for the purpose of accelerating the movement of the valve in a short stroke of the lever and permitting some lost motion 45 between the pin 79 and the arm after the valve has been sufficiently moved to deliver the liquid. A limitation is imposed upon the valve-movement in both directions by the projecting-lugs 41, which engage the smooth 50 surface of the segmental portion of the bell-crank lever, it being understood that when one of the lugs 41 engages one or the other end of said segmental portion, the movement of the valve in that direction will cease. By 55 thus oscillating the valve, the aperture 42 is moved from its position of registry with the passage 45 leading into the reservoir and through which passage liquid passes into the valve-chamber. The aperture 42 is caused 60 in its movement to register with the passage through the spraying-nozzle 46, so that, under the proper conditions, the liquid may be sprayed onto the surface of the stamp. As the aperture 42 passes from its position of 65 registry with the passage 45, to its position

of registry with the passages through the nozzle 46, the aperture 43 moves into registry with the tube 26. During this operation, the air drawn into the chamber surrounding the plunger 61 is forced by the valve 71 into 70 the passage 58, and thence into the tube 29, and thence into the valve 24, and, since this valve has been set for operation, the air passes through the passage 28 into the reservoir to fill the space above the liquid and 75 also through the aperture 25 into the tube 26, to thus force air into the chamber of the valve 35 and drive the liquid therein through the aperture 42 and through the nozzle 46 to spray the same upon the surface of the 80 stamp. The groove 73, in the plunger, performs an important function in the operation of the machine, since, without the same, the air in the chamber of the handle might become so compressed as to render it difficult 85 to quickly and easily depress the plunger. By forming the groove 73, as shown, before any perceptible retardation in the downward movement of the plunger can take place, the lower end of said groove will 90 have passed the lower portion *a* of the frame, thus relieving pressure in the handle-chamber. Furthermore, the upward movement of the plunger will cause air to be drawn into the handle-chamber through said 95 groove 73. From the foregoing, it will be seen that the sequence of operation is to draw in air through the suction passages 70 and 73 into the compression-chamber on the up-stroke 100 of the plunger. This same movement accomplishes one-half of the feeding operation of the stamp and returns the cutter-blade to a normal, inoperative position. At the same time, the valve 35 is turned so that 105 the spraying-nozzle ceases to operate and the said valve may receive from the reservoir, under air pressure, a predetermined quantity of liquid. The down-stroke of the plunger forces the air against the valve 71, 110 closing the ports 70, forces the air through the various passages and tubes, turns the valve 35 for coöperation with the spraying-nozzle, completes the feed-movement of the feed-drum and the cutting-movement of the 115 cutter-blade. Simultaneously with these operations, the surface of the stamp is sprayed with liquid and the stamp is pressed by the flat bottom surface of the cutter-head firmly upon the article to which it is applied. The 120 pressure of the cutter-head upon the stamp causes the liquid to spread in all directions so that every portion of the applied surface thereof is moistened. Hence, it is not essential that the spray should be applied directly to the entire surface of the stamp. Preliminary adjustments of the feeding-drum upon its axis or shaft 118 can be accomplished without disturbing the relation of the mutilated-gears 116 and 117, by pulling out the 125 130

detent-pin 135 to remove its wedge 136 from engagement with the segmental-ratchet 132. This may be necessary for the purpose of preliminarily setting the stamp preparatory 5 to feeding the same; that is to say, if in threading the device with the web too much or too little of the web is projected through the slot of the base-plate. This provides against waste of any of the stamps. This 10 adjustment is accomplished within the limits of the movement of the pawl 134 prescribed by the engagement of its pin 137 with either one or the other of the flat surfaces at opposite extremes of the ratchet- 15 segment 132, this adjustment being less than the length of the stamp. Adjustment of the feed-drum may be produced by turning the screw 145 in the end of the adjusting-sleeve 144 to cause its beveled flanges to coöperate 20 with the beveled flanges of the feed-drum, movement of said sleeve in one direction or the other causing the expansion or contraction of the flexible members of the said drum to increase or decrease the diameter 25 thereof. This adjustment is for the purpose of causing the feed-drum, for each complete reciprocation of the plunger 61, to be just enough to feed the stamp its full length or from division to division between stamps. 30 This adjustment of the drum being accomplished and the stamp being properly set as described absolutely accurate feeding of the web is accomplished indefinitely the full length of a stamp for each reciprocation of 35 the plunger. The amount of liquid sprayed upon the surface of the stamp is regulated by the adjustment of the plug 44 in the end of the valve 35, so as to increase or decrease the size of the chamber of said valve. By 40 turning the valve 24, so as to close the opening into the reservoir, whatever the position of valve 35 may be, the liquid in the reservoir will be so confined that no leakage or drip will occur. Consequently, there is 45 no liability of a stamp, a portion of which may be projecting from the face-plate, becoming moistened, except when desired, through operation of the plunger. The liquid being thus shut off, the machine can be 50 inspected, readjusted, turned upside down, or manipulated in any manner without having the liquid leak or spill from the reservoir. When the liquid is thus shut off, or when the reservoir is empty, the machine 55 can be used for vending stamps or other suitable articles.

As previously pointed out, one of the important features of my invention resides in the mode of moistening the surface of the 60 stamps and in connection with the mechanism thereof I desire it distinctly understood that my invention comprehends the broad idea of means of spraying the water or liquid upon the stamp or article to which 65 it is to be attached and also the broad idea

of means of spraying a measured quantity of said water, and the further broad idea of means of operating the spraying-device by a plunger, whether that plunger be a column of air or a mechanical device. To illustrate 70 the breadth and scope of this portion of my invention, reference is made to Fig. 9, showing an alternative form of my invention and wherein the valve is constructed in substantially the same manner as described with 75 reference to Fig. 2, but is threaded into the reservoir by fine screw-threads 156 of low pitch and has at its outer end two projecting-lugs 157, affording a space between them within which operates a fixed pin 158, set 80 in the frame of the reservoir. This pin limits the oscillatory movement of the valve-sleeve and thus prevents it from being moved in either longitudinal direction farther than the limits prescribed by the distance between 85 the lugs. A piston, the head 159 of which is smooth, is threaded into the valve-chamber by a coarse or quick thread 160, and the other end of the plunger is provided with a gear 161, to be driven by the bell-crank lever segment 39, in the same manner as described with reference to Fig. 15. The screw-plug 162 is adjustable in the valve-chamber to vary the size thereof and regulate the amount of water it may contain. 90 Reciprocation of the plunger 61, actuating the bell-crank lever, will cause its segment 39 to oscillate the piston; but, owing to the coarse-thread connection between it and the valve, the latter is first rotated to cause its 100 longitudinal movement in the valve chamber and thus bring the aperture 42 into registry with the spraying-device. This registry being produced, the movement of the valve ceases and the further rotation of 105 the piston causes it to move endwise in the valve-chamber and thus create pressure upon the body of water therein to force the same through the aperture into the spraying-nozzle and therefrom upon the surface of the 110 stamp. Thus it will be seen that variations and alternative constructions are clearly within the broad idea of means of my invention, as above pointed out.

Among the other features upon which I 115 have laid stress, I consider the feeding-pins 154 and the general construction and arrangement of my feeding mechanism as important, since the pins not only act to insure a positive feeding of the strip of stamps, but also prevent the strip from being pulled through or out of the machine by hand,—unless torn or mutilated,—which, in combination with the drum-operating mechanism and its peculiar construction and arrangement of parts, act as a stop or check on the 125 feed-drum being moved more than a portion of the length of a single stamp at any time other than by the intended operation of the plunger.

Though I have emphasized the moistening liquid as being applied to the stamp, it is clearly evident that, by turning the spraying-nozzle 46-47 so as to direct the spray down, the object to which the stamp is to be affixed will be moistened instead and that pressing the stamp on the moistened surface by the plunger the same result will be attained as when the spray is driven up 5 against the stamp. Therefore, I wish it to be understood that I claim both ways as being broadly within the scope of my invention.

Having thus described my invention, what 15 I claim and desire to secure by Letters Patent is:

1. A machine having, in combination, a receptacle having means for supporting a rotating web of articles; means for delivering 20 articles from said receptacle comprising a reciprocating rack-bar, a rotary feed-wheel, and gearing connecting the bar and wheel; cutting means for severing the articles at the completion of the operation of 25 the delivering means; and means for spraying liquid directly upon the article to be delivered from the machine for the purpose of affixing said article to another.

2. A machine having, in combination, a 30 reciprocating plunger; a receptacle, having means for supporting a rotating web of articles, arranged in rear of said plunger; feeding mechanism arranged between the plunger and receptacle; cutting mechanism; connections between the plunger and cutter and 35 feeding mechanism for actuating the same; and moistening mechanism movable relatively to the receptacle and located directly below the same and in rear of and remote 40 from the feeding mechanism.

3. A machine having, in combination, a receptacle having means for supporting a rotating web of articles; means for delivering the articles intermittently from said machine, comprising a reciprocating rack-bar, a feed-wheel, and gearing connecting the bar and wheel; means for cutting the articles from the web at the end of each complete delivery operation; and means for projecting moisture directly upon the article 45 to be delivered prior to its being affixed.

4. A machine having, in combination, means for intermittently feeding articles from a web; means for cutting the articles 55 from the web one-by-one; means for applying liquid to the surface of the articles; and means for applying the articles to a given surface; the said liquid applying means including an intermittently-operated measuring valve for delivering a predetermined amount of liquid to be applied.

5. A machine having, in combination, means for feeding articles from a web; means for cutting the articles from said web; 65 and moistening means for applying liquid to

said articles, said moistening means including a measuring-device by which to measure the amount of liquid to be used in each operation.

6. A stamp-affixing machine having, in combination, a vertically reciprocating plunger; a closed receptacle for a rotary reel of stamps arranged adjacent the plunger; means in said receptacle for supporting said reel; feeding mechanism arranged between the plunger and receptacle and co-operating with said plunger; moistening means, arranged below the receptacle and feeding means and also in rear of the latter; and means actuated by the plunger for causing the moistening means to project liquid upon the stamp.

7. A stamp-affixing machine having, in combination, a cutter; means for actuating the same; means for delivering stamps to the cutter; a liquid reservoir beneath said delivery means; and means for spraying the liquid directly upon the stamp beyond the cutting position.

8. A stamp-affixing machine including a reciprocating cutter; a feeding mechanism; a spraying means including a spraying nozzle extending to position to spray a stamp after it has passed the cutter; and means for actuating the several parts including a connection between the cutter-actuating means and feeding means; and means controlled by the cutter-actuating means for operating the spraying means to direct the sprayed liquid upon the stamps just before being cut off.

9. A stamp-affixing means having, in combination, a stamp receptacle having means upon which a stamp-reel may be journaled, a reciprocating plunger carrying at one end a cutting device; a feeding mechanism including a rotary drum arranged at one side of the cutting device and below the said receptacle; a moistening means arranged below the feeding device and remote from the point of delivery of the stamp and having a spraying-device extending to position to spray a stamp after it has passed the cutting-device; and means for actuating the several parts to feed a stamp to the cutting mechanism and for spraying liquid directly upon the stamp to enable the latter to be affixed to an article.

10. A stamp-affixing machine having, in combination, a stamp-feeding means; a stamp-cutting means; a spraying nozzle extending to position to spray a stamp after it has passed the cutting means and directed toward the stamp to be delivered; and means for driving liquid through said nozzle.

11. A stamp-affixing machine having, in combination, a stamp-feeding means; a stamp-cutting means; and stamp-moistening means, the moistening means being provided with a measuring device, an upwardly in-

clined spraying device, and having means for intermittently operating the measuring device.

12. A stamp-affixing machine having, in combination, a receptacle for stamps provided with a movable cover; a moistening device, for applying liquid to the stamps, movable into inoperative position; and the moistening device and the said cover having coöperating means for locking the cover when the moistening means is in an operative position.

13. A stamp-affixing machine having, in combination, a receptacle for stamps including a movable cover; a moistening-device movable into inoperative position; the cover and the device having coöperating means whereby one may lock the other, said means performing its functions as one of the parts is moved into operative position; and means for locking the said movable part in its operative position.

14. A moistening device for stamp-affixing machines having, in combination, a reservoir for the liquid; an oscillating valve for controlling the amount of liquid to be delivered from the reservoir; mechanical means for oscillating said valve; and means adapted to create pressure in the reservoir for acting upon the liquid to drive the same through and from said controlling valve.

15. A moistening-device for stamp-affixing machines comprising a reservoir for the liquid; an oscillating measuring-device for measuring a definite quantity of the liquid for delivery from the reservoir; a spraying nozzle for coöperating with said measuring-device; means for oscillating said measuring-device, and means for driving the liquid through the measuring-device and the nozzle.

16. A moistening device for stamp-affixing machines comprising a reservoir; a liquid outlet at the bottom of said reservoir; a valve located in said reservoir in coöperative relation to the liquid outlet to control the outlet of the liquid; pneumatic means for ejecting the liquid from the reservoir through the valve; and means for intermittently actuating the valve and for similarly controlling the pneumatic means.

17. A moistening-device for stamp-affixing machines comprising a reservoir; a liquid-inlet at the top thereof; a liquid-outlet at the bottom thereof; means for controlling the liquid-outlet; a movable air-inlet at the top of the reservoir; a passage therefrom to the reservoir; and a tube connecting the air-inlet with the liquid-outlet.

18. A moistening-device for stamp-affixing machines comprising a reservoir having in its bottom a liquid-outlet; an oscillating measuring-device controlling the liquid outlet; and means extending through the res-

ervoir from its top to the measuring-device 65 for forcing the liquid from the latter.

19. A moistening-device for stamp-affixing machines comprising a reservoir having a forward extension at its bottom and a liquid-outlet in said extension; an air-inlet 70 at the top of said reservoir; and an oscillating valve housed in said reservoir at the top of the latter for controlling the air-inlet.

20. A moistening-device for stamp-affixing machines comprising a reservoir having 75 a forward extension at its bottom; a liquid-outlet in said extension of said reservoir; an oscillating measuring-device for controlling said liquid-outlet; a spraying nozzle fixed in said outlet and coöperating with said measuring-device; and means for driving the liquid from said measuring-device through said nozzle.

21. A stamp-affixing machine having, in combination, a cutting mechanism; a feeding mechanism; a face-plate interposed between the feeding mechanism and the cutting mechanism and carrying a part of the cutting mechanism; a stripper-plate interposed between the face-plate and the feeding mechanism and coöperating with the latter to strip the stamps therefrom; means by which the stamps may be affixed; and means for actuating the cutting and feeding mechanisms. 95

22. A stamp-affixing machine having, in combination, a cutting mechanism; a feeding mechanism; a face-plate interposed between said mechanisms; a strip-guide coöperating with the feeding mechanism; a stripper-plate coöperating with the strip-guide and the feeding mechanism; means by which the stamps may be affixed; and means for actuating the cutting and feeding mechanisms. 100

23. A stamp-affixing machine having cutting mechanism; feeding mechanism including a reciprocatory plunger; and a moistening mechanism, the latter comprising a pneumatic device including a compression-mechanism surrounding said plunger, and connections between the compression-mechanism and the moistening-device. 110

24. A stamp-affixing machine comprising a handle having a compression-chamber; a reciprocatory part for forcing the air from said chamber; a moistening-device comprising a pneumatic sprayer; and connections between said compression-chamber and said sprayer. 115

25. A machine having, in combination, means for intermittently feeding articles from a web; means for cutting articles from the web one-by-one; means for supplying liquid so as to attach the articles to an object; and means for applying the articles to an object; the said liquid-supplying means including an intermittently-operated meas- 120 125

uring valve for measuring the amount of liquid to be supplied into the valve.

26. A moistening-device for stamp-affixing machines comprising a reservoir; a liquid-outlet therefrom; means for controlling the liquid-outlet including a delivery valve; and means for applying air pressure to the liquid in the reservoir for the purpose of driving the liquid from the reservoir.
- 10 27. A stamp-affixing machine having, in combination with the frame thereof, a feeding-drum for delivering stamps; a reservoir hinged to the frame; a strip-guide carried by the reservoir and having slots therein, the said feeding-drum being provided with radial pins for entering the slots of the strip-guide.

28. The combination of a receptacle for gummed articles, feeding and affixing means for said articles, a liquid reservoir, and air compression means and liquid feeding means controlled by the feeding means so that the compression of air will coöperate with the moisture feeding means and cause the liquid controlled thereby to be sprayed upon the articles to be affixed.

29. In a stamp-affixer, the combination with a frame and an affixing member movable into and out of affixing position, of a liquid receptacle having a discharge chamber provided with an orifice leading therefrom, a device movable in said chamber, and means actuated by the affixing member for operating said device to eject moisture directly upon the stamp.

30. In a stamp-affixer, the combination with a frame and an affixing member movable into and out of affixing position, of a liquid receptacle provided with a discharge orifice, a wall forming a chamber in the receptacle into which the orifice leads, a device located in the chamber and means actuated by the affixing member for operating said device to expel liquid from said chamber directly upon the stamp.

31. A stamp-affixer having in combination with the frame thereof, a reciprocating affixing member, a liquid receptacle provided with a discharge orifice, a chamber adjacent said receptacle and communicating with the latter by said discharge orifice, a device operating in the chamber under control of the affixing member, and means for discharging liquid from the chamber through said device upon the stamp.

32. In a stamp-affixer, the combination with a frame and an affixing member movable into and out of affixing position, of a liquid receptacle having a discharge cham-

ber therein and provided with an orifice leading from said chamber, a device reciprocating in the latter, and means actuated by the affixing member for operating said device.

33. In a stamp-affixer, the combination with a frame and an affixing member movable into and out of affixing position, of a liquid receptacle provided with a discharge orifice located near the bottom of the side wall of the receptacle, a partition wall arranged in the receptacle near the bottom of the latter to separate a portion of the liquid in the vicinity of the orifice from the main body of the liquid, a device movable relatively to the side wall of the receptacle between the bottom of the latter and said partition wall, and means actuated by the affixing member for operating the device.

34. In a stamp-affixer, the combination with a frame, a reciprocating affixing member, and stamp feeding mechanism, means for holding a strip of stamps, a stamp guide-way leading therefrom, said guide-way being capable of displacement on the frame to permit access to the interior of the holding means, and a lock for retaining said parts in operative position on the frame.

35. A stamp affixing machine comprising, a stamp affixing plunger, means operated by the stamp affixing plunger for feeding one stamp of the strip into an affixing position, means for severing and affixing the stamp, and means operated by the stamp affixing plunger for causing the ejection of moisture onto the under surface of the said stamp after said stamp has passed through the severing device and as it moves into the affixing position.

36. A moistening device for stamp affixing machines having in combination a reservoir for the liquid; a valve for controlling the amount of liquid to be delivered from the reservoir; means for actuating said valve; said valve being provided with oppositely disposed apertures through which the liquid may enter and be ejected; and means adapted to create pressure in the reservoir for acting upon the liquid to drive the same through and from the apertures in said valve.

In testimony whereof I have hereunto signed my name in the presence of two subscribing witnesses.

LANSING ONDERDONK.
